UNITED STATES PATENT OFFICE.

ERIC F. WILLER, OF MILWAUKEE, WISCONSIN, ASSIGNOR TO CHARLES ABRESCH CO.,
OF MILWAUKEE, WISCONSIN, A CORPORATION OF WISCONSIN.

DESIGN FOR AN AUTOMOBILE-BODY.

58,173.

Specification for Design. Patented June 14, 1921.

Application filed July 9, 1920. Serial No. 395,167. Term of patent 7 years.

To all whom it may concern:

Be it known that I, ERIC F. WILLER, a citizen of the United States, residing at Milwaukee, in the county of Milwaukee and State of Wisconsin, have invented a new, original, and ornamental Design for an Automobile-Body, of which the following is a description, reference being had to the accompanying drawing, forming part thereof.

The drawing is a perspective view of an

automobile showing my new design of automobile body.

I claim:

The ornamental design for an automobile body, as shown.

ERIC F. WILLER.
